UNITED STATES PATENT OFFICE.

MAUNSELL BOWERS JACKSON, OF TORONTO, ONTARIO, CANADA.

STARTER FOR ENGINES.

Application filed March 17, 1926. Serial No. 95,320.

This invention relates to starters for internal combustion engines of the type in which the starter pinion is manually moved into meshing engagement with the engine gear, 5 and more particularly to the type of starter disclosed in my prior applications Serial Number 67,577, filed Nov. 7, 1925, and Serial Number 81,014, filed Jan. 13, 1926, in which a continuous movement of each operating 10 mechanism for meshing the starter with the engine gear, axially moved the pinion and rotated it as necessary to align it with the gear. Each mechanism includes a finger pivoted on an arm, the finger being adapted 15 to engage the pinion eccentric to its axis. The object of the present invention is to so carry the finger that, if it is swung by the pinion from its operative position to an inoperative position, it will have no appreciable tendency to axially move the pinion towards the gear.

I attain my object by providing the arm with a resilient stop adapted to limit the rocking movement of the finger on its pivot 25 towards the pinion to position it in its operative position. The finger is free to swing inward on its pivot, that is to swing in a direction away from the end of the pinion, without tensioning nor actuating any re-setting means which would impart a rocking movement to the finger to swing it towards the end of the pinion and thus cause the latter to be axially moved. A fixed abutment is provided for re-setting the finger to 30 its normal position and for limiting the movement of the finger carrying arm away from the pinion. The resilient stop is also adapted to re-set the finger if it is thrown past the face of the end of the pinion into 35 engagement with the periphery of the said end of the pinion. In this inoperative position, the finger has no tendency to apply any axial force to the pinion. The constructions are hereinafter more fully described and 40 illustrated in the accompanying drawings in which

Fig. 1 is a side elevation, partly in section, of my starter showing the finger in its operative position and the finger carrying 45 arm in its initial position;

Fig. 2 a cross section on the line 2—2 in Fig. 1;

Fig. 3 a side elevation showing the position of the parts when the pinion teeth meet 50 end to end with the gear teeth;

Fig. 4 a side elevation showing the position of the parts, with the finger in an inoperative position, after the engine has been started and before the switch is opened;

Fig. 5 a sectional detail on the line 5—5 60 in Fig. 4;

Fig. 6 a side elevation showing the finger moved to a second inoperative position; and

Fig. 7 a side elevation of a modified form 65 of the invention.

In the drawings like numerals of reference indicate corresponding parts in the different figures.

1 is an electric motor provided with an extended armature shaft having long pitched 70 threads 3 formed thereon. A pinion 4 threaded on the shaft 2 is adapted to be manually moved, both axially and rotarily, into mesh with a gear 5 connected with the crank shaft of an engine (not shown), the 75 common practice being to secure this gear to the engine flywheel. A bell crank 6 journaled on a stud 7 is adapted to be oscillated by any suitable, manually operated mechanism such as the foot pedal or plunger 8 shown in Fig. 1. On an arm 6^a of the bell crank is pivoted, by means of a pin 9^b, a finger 9 which is provided with a pair of spaced lugs 9^a. The finger is also provided 80 with teeth 9^d and 9^e adapted to engage, seriatim, a peripheral flange or collar 4^a on the inner end of the pinion. Preferably the flange is serrated for engagement with the finger teeth.

The arm 6^a is adapted to be received between the spaced lugs 9^a. To limit the outward swinging movement of the finger on its pivot 9 for positioning the finger in its operative position, I provide a resilient stop 21 adapted to extend across the gap between 95 the lugs and to engage the back of the arm 6^a. The resilient stop is formed from a substantially U-shaped piece of wire having coil springs 21^a formed intermediate the ends of its leg portions. The springs are loosely disposed on the opposite ends of the pin 9 and the loop or hook portion 21^b joining the springs passes round behind the lugs. The free ends of the stop are secured to the sides of the finger. Preferably the finger is 100 loosely mounted on its pivot so that it will tend, by means of gravity, to fall to its operative position.

It is obvious that by rocking the arm 6^a 110 the finger will axially move the pinion to-

wards the gear 5 and into meshing engagement therewith if the pinion teeth are in alignment with the spaces between the engine gear teeth when the pinion and gear 5 come together. If the teeth of the pinion and gear meet end to end when the pinion is being axially moved into mesh with the gear, the axial movement of the pinion towards the gear will be stopped, which will 10 result in first one tooth 9^d, and if necessary, the second tooth 9^e rotating the pinion sufficiently to cause its teeth to clear the teeth of the gear. This is due to the finger swinging in a plane located at one side of the 15 axis of the pinion and having its teeth at an angle to said axis. When the finger has rotated the pinion teeth past the contacting gear teeth it again moves the pinion axially of the shaft and into meshing engagement 20 with the gear teeth.

The other arm 6^b of the bell crank 6 is adapted to engage a spring pressed contact 11 of an ordinary plunger type switch and move it to close the starter motor circuit. 25 With this arrangement the motor 1 is energized when the pinion teeth are in meshing engagement with the gear teeth. The shaft 2 is thus rotated to thread the pinion, which is held from rotation by the gear, 30 along the shaft and fully into mesh with the gear. When the pinion engages a collar 14 formed on or secured to the shaft its axial movement is stopped and it rotates with the shaft to drive the gear.

35 When the engine is started the pinion is automatically returned to its inoperative position in the usual manner. The axial return movement of the pinion is limited by shoulders 15 formed on the outer ends of the 40 threads 3. The pinion is releasably retained in its inoperative position by any suitable means such as a spring pressed ball 16 carried in the shaft and adapted to frictionally engage a recess formed at the inner end of 45 the pinion.

If the motor switch is closed when the engine starts, the pinion when moving to its normal position will engage the finger 9 and swing it inwardly into engagement with a 50 stop 22 carried by the arm 6^a, see Fig. 4. In this inoperative position the finger has no appreciable tendency to move the pinion towards the gear. When the operator removes his foot from the foot device 8, a 55 spring 19 returns the latter and the bell crank 6 to their normal positions. During this return movement the lugs 9^a are adapted to be engaged by a fixed abutment 23 which re-sets the finger 9 to its operative position 60 and engages the arm 6^a to limit its movement under the action of the spring 19. The stop 22 limits the inward swinging movement of the finger to position the lugs for engagement with the abutment 23.

65 If the pedal 8 should be inadvertently

stepped on while the engine is running, the finger would move the pinion into contact with the ends of the gear teeth which would cause the pinion to be rotated. This would result in the finger being thrown inwardly, 70 by the revolving pinion, into an inoperative position in which the finger would have no tendency to apply axial force to the pinion. The pinion is thus free from the action of forces tending to hold it in contact with the 75 revolving gear.

The above results are also obtained in cases where the engine makes a false start (fires once or twice only) and the operator tries to mesh the pinion and gear while the latter 80 is rocking in its normal direction of rotation. Should the operator try to mesh the pinion and gear while the latter is rocking or revolving in the direction of rotation opposite to its normal direction of rotation the serrations on the pinion will engage a tooth on the finger and throw the latter outwardly, as shown in Fig. 6, to a second inoperative position in which the finger engages the periphery of the collar 4^a. The 85 coil springs 21^a of the resilient stop are thus tensioned and are adapted, when the arm 6^a is returned to its normal position, to re-set the finger to its operative position. The tensioning of the springs 21^a has no tendency 90 to cause the pinion to be moved axially of the shaft.

In Fig. 7 is shown a modified form of my invention applied to the starter shown in my prior applications in which starter the 100 finger is swung inwardly on its pivot to its operative position. The finger 9^g is formed as a lever pivoted intermediate its ends on the arm 6^a. The end of the lever remote from the pinion engaging tooth 9^h is provided with a weight just sufficient to rock the toothed end of the lever outwardly to its operative position which is determined by a resilient stop 21^c. A fixed abutment 105 23^a is provided for engagement with the 110 weighted end of the lever to ensure that the latter will be positioned in its operative position when the arm 6^a is returned to its initial position.

What I claim is:

1. An engine starter drive including a rotatable shaft; a starter pinion mounted thereon for rotary movement therewith and for longitudinal movement thereof to mesh with a gear of the engine to be started; a pivoted finger adapted to engage the pinion eccentric to its axis; and means for actuating the finger to cause such longitudinal movement of the starter pinion and to cause a rotary movement thereof if the teeth on the pinion meet end to end with the teeth on the gear, the finger being adapted to be swung in either direction of movement out of its operative position by the pinion if the latter is rotated by the gear, the finger when 115 120 125 130

in an inoperative position having no appreciable tendency to move the pinion longitudinally of the shaft.

2. An engine starter drive including a rotatable shaft; a starter pinion mounted thereon for rotary movement therewith and for longitudinal movement thereof to mesh with a gear of the engine to be started; a pivoted finger adapted to engage the pinion eccentric to its axis; means for actuating the finger to cause such longitudinal movement of the starter pinion and to cause a rotary movement thereof if the teeth on the pinion meet end to end with the teeth on the gear; and resilient means for limiting the outward rocking movement of the finger on its pivot for positioning the finger in its operative position, the said means being adapted to permit the pinion to swing the finger inward to an inoperative position without exerting any force on the finger which would tend to move the pinion longitudinally of the shaft.

3. An engine starter drive including a rotatable shaft; a starter pinion mounted thereon for rotary movement therewith and for longitudinal movement thereof to mesh with a gear of the engine to be started; a pivoted finger adapted to engage the pinion eccentric to its axis; means for actuating the finger to cause such longitudinal movement of the starter pinion and to cause a rotary movement thereof if the teeth on the pinion meet end to end with the teeth on the gear; resilient means for limiting the outward rocking movement of the finger on its pivot for positioning the finger in its operative position, the said means being adapted to permit the pinion to swing the finger inward to an inoperative position without exerting any force on the finger which would tend to move the pinion longitudinally of the shaft; and means for re-setting the finger in its operative position when it has been withdrawn from engagement with the pinion.

4. An engine starter drive including a rotatable shaft; a starter pinion mounted thereon for rotary movement therewith and for longitudinal movement thereof to mesh with a gear of the engine to be started; a pivoted finger adapted to engage the pinion eccentric to its axis; means for actuating the finger to cause such longitudinal movement of the starter pinion and to cause a rotary movement thereof if the teeth on the pinion meet end to end with the teeth on the gear; resilient means for limiting the outward rocking movement of the finger on its pivot for positioning the finger in its operative position, the said means being adapted to permit the pinion to swing the finger inward to an inoperative position without exerting any force on the finger which would tend to move the pinion longitudinally of the shaft; a lug carried by the finger; and an abutment adapted to engage the lug to re-set the finger in its operative position and adapted to engage the arm to limit its return movement; and a stop carried by one of said arm and finger parts adapted to engage the other part to limit the inward swinging movement of the finger to position the lug for engagement with the abutment.

5. An engine starter drive including a rotatable shaft; a starter pinion mounted thereon for rotary movement therewith and for longitudinal movement thereof to mesh with a gear of the engine to be started; a pivoted arm; a finger pivoted on the arm and adapted to engage the pinion eccentric to its axis, the finger having a lug; means for actuating the arm to cause such longitudinal movement of the pinion and to cause a rotary movement thereof if the teeth on the pinion meet end to end with the teeth on the gear; and a coil spring disposed on the finger pivot and having an end engaged with the finger, and having a hook engaged with the lug, the hook being adapted to engage the arm to limit the rocking movement of the finger on its pivot in one direction to position the finger in its operative position, the said spring and hook being adapted to permit the pinion to swing the finger to an inoperative position without exerting any force on the finger which would tend to move the pinion longitudinally of the shaft.

6. An engine starter drive including a rotatable shaft; a starter pinion mounted thereon for rotary movement therewith and for longitudinal movement thereof to mesh with a gear of the engine to be started; a pivoted arm; a finger pivoted on the arm and adapted to engage the pinion eccentric to its axis, the finger having a lug; means for actuating the arm to cause such longitudinal movement of the pinion and to cause a rotary movement thereof if the teeth on the pinion meet end to end with the teeth on the gear; a resilient stop carried by the finger and adapted to engage the arm for limiting the rocking movement of the finger on its pivot in one direction for positioning the finger in its operative position, the said stop being adapted to permit the pinion to swing the finger to an inoperative position without exerting any force thereon which would tend to move the pinion longitudinally of the shaft; an abutment adapted to engage the lug to re-set the finger in its operative position and adapted to engage the arm to limit its return movement; and a stop carried by one of said arm and finger parts adapted to engage the other part to limit the inward swinging movement of the finger to position the lug for engagement with the abutment.

7. An engine starter drive including a rotatable shaft; a starter pinion mounted thereon for rotary movement therewith and for longitudinal movement thereof to mesh with a gear of the engine to be started; a pivoted arm; a finger pivoted on the arm and adapted to engage the pinion eccentric to its axis, the finger being adapted to move

by gravity towards its operative position; and resilient means for limiting the rocking movement of the finger on its pivot for positioning it in its operative position, the said means being adapted to permit the pinion to swing the finger upward to an inoperative position without exerting any force on the finger which would tend to move the pinion longitudinally of the shaft.

10 8. An engine starter drive including a rotatable shaft; a starter pinion mounted thereon for rotary movement therewith and for longitudinal movement thereof to mesh with a gear of the engine to be started; a pivoted arm; a finger pivoted on the arm and adapted to engage the pinion eccentric to its axis; means for actuating the arm to cause such longitudinal movement of the pinion and to cause a rotary movement thereof if its teeth meet end to end with the teeth on the gear; a resilient stop normally untensioned by the finger for limiting the rocking movement of the finger on its pivot towards its operative position; and a fixed abutment for re-setting the finger to its operative position when the arm is in its initial position.

9. An engine starter drive including a rotatable shaft; a starter pinion mounted thereon for rotary movement therewith and for longitudinal movement thereof to mesh with a gear of the engine to be started; a pivoted arm; a finger pivoted on the arm and adapted to engage the pinion eccentric to its axis; means for actuating the arm to

cause such longitudinal movement of the pinion and to cause a rotary movement thereof if its teeth meet end to end with the teeth on the gear; a resilient stop normally untensioned by the finger for limiting the 40 rocking movement of the finger on its pivot towards its operative position; and means for re-setting the finger to its operative position when the arm is in its initial position.

10. An engine starter drive including a rotatable shaft; a starter pinion mounted thereon for rotary movement therewith and for longitudinal movement thereof to mesh with a gear of the engine to be started; a pivoted finger adapted to engage the pinion eccentric to its axis; means for actuating the finger to cause such longitudinal movement of the starter pinion and to cause a rotary movement thereof if the teeth on the pinion meet end to end with the teeth on the gear, the finger being adapted to be swung in either direction of movement out of its operative position by the pinion if the latter is rotated by the gear, the finger when in an inoperative position having no appreciable 55 tendency to move the pinion longitudinally of the shaft; and means for demeshing the pinion automatically when the gear is driven by the engine, the finger being adapted to permit the demeshing of the pinion without imparting movement to the finger actuating means.

Signed at Toronto, Canada, this 8th day of March, 1926.

MAUNSELL BOWERS JACKSON.
